US00D338731S

United States Patent [19]

Byland et al.

[11] Patent Number: Des. 338,731

[45] Date of Patent: ** Aug. 24, 1993

[54] **IMPLANTABLE MEDICAL HOUSING**

[75] Inventors: James K. Byland, St. Paul; Thomas I. Ceballos, Spring Lake Park, both of Minn.

[73] Assignee: Medtronic, Inc., Minneapolis, Minn.

[**] Term: 14 Years

[21] Appl. No.: 766,702

[22] Filed: Sep. 26, 1991

[52] U.S. Cl. D24/167; D24/155

[58] Field of Search D24/155, 167, 169, 187; 128/419.P, 419.PG, 419.PS, 419.D

CLAIM

The ornamental design for an implantable medical housing, as shown and described.

DESCRIPTION

FIG. 1 is a perspective view of an implantable medical housing showing our new design, viewing from the front and right side thereof;

FIG. 2 is an elevational view of the left side thereof;

FIG. 3 is an elevational view of the front side thereof;

FIG. 4 is an elevational view of the right side thereof;

FIG. 5 is a plan view of the top side thereof;

FIG. 6 is an elevational view of the back side thereof;

and,

FIG. 7 is a plan view of the bottom side thereof.
